ARMED FORCES EXPEDITIONARY SERVICE MEDAL

Jay C. Morris, Alexandria, Va., assignor to the United States of America as represented by the Secretary of the Army

Filed Aug. 28, 1964, Ser. No. 81,504

Term of patent 14 years

(Cl. D29—19)

(Granted under Title 35, U.S. Code (1952), sec. 266)

FIG. 2

FIG. 1

FIG. 4

FIG. 3

FIG. 1 is a front elevational view of an armed forces expeditionary service medal, showing my new design;

FIG. 2 is a right side elevational view thereof, the projecting portions of the rear having been omitted for convenience of illustration;

FIG. 3 is a rear elevational view of an armed forces expeditionary service medal, showing my new design; and

FIG. 4 is a right side elevational view thereof, the projecting portions of the front having been omitted for convenience of illustration.

The essential features of my design are shown in solid lines.

The design described herein may be reproduced and used by or for the Government for governmental purposes without the payment to me of any royalty thereon.

I claim:

The ornamental design for an armed forces expeditionary service medal, as shown and described.
